Primary Examiner — Ian Simmons

Assistant Examiner — Shannon Morgan

(74) Attorney, Agent, or Firm — Richard T. Ogawa; Ogawa P.C.

(57) **CLAIM**

The ornamental design for a display screen or portion thereof with graphical user interface, as shown and described.

DESCRIPTION

FIG. 1 is a front view of a first embodiment of a display screen or portion thereof with graphical user interface showing our new design; and,

FIG. 2 is a front view of a second embodiment of a display screen or portion thereof with graphical user interface showing our new design.

The broken lines shown in the drawings depict portions of the display screen and graphical user interface that form no part of the claimed design.

1 Claim, 2 Drawing Sheets(56)
